UNITED STATES PATENT OFFICE.

EDWARD H. HEBENSTREIT, OF NOKOMIS, ILLINOIS.

RAILROAD SWITCH.

Application filed December 4, 1922. Serial No. 604,872.

To all whom it may concern:

Be it known that I, EDWARD H. HEBENSTREIT, a citizen of the United States, residing at Nokomis, in the county of Montgomery and State of Illinois, have invented certain new and useful Improvements in Railroad Switches, of which the following is a specification.

This invention relates to railroad switches and has special reference to a switch adapted particularly for use in mines.

More particularly the invention relates to switches for mine railroads operable from over-head so that the operator of the mine car or train does not have to stop his train and get on the ground in order to manipulate the switch.

An important object of the invention is to improve the general construction of devices of this character, especially in the efficiency of the device, and the facility with which it may be operated.

A second important object of the invention is to provide an improved arrangement of switch throwing lever adapted for attachment overhead of the railroad tracks.

The third important object of the invention is the provision of a device of this character which can be adjusted to fit the varying conditions in a mine or the like.

With the above and other objects in view as will be hereinafter apparent, the invention consists in general of certain novel details of constructions and combinations of parts hereinafter fully described, illustrated in the accompanying drawings and specifically claimed.

In the accompanying drawings wherein like numerals are employed to designate like parts throughout the same,

Figure 1 is a side elevation of my apparatus in an assembled condition;

Figure 2 is a section taken on line 2—2 of Figure 1 and looking in the direction of the arrow;

Figure 3 is a section taken on line 3—3 of Figure 1 looking in the direction of the arrow;

Figure 4 is a view taken substantially on the line 4—4 of Figure 1 looking in the direction of the arrow, and

Figure 5 is a fragmentary detail view of a portion of my device.

In the drawings, wherein for the purpose of illustration is shown a preferred embodiment of my invention, the numeral 10 designates main line sections of a track, being provided with turn-out 11 and switch points 12, the latter being connected together in the usual manner by a tie rod 13 so that they move in unison. On both sides of the tracks, are located suitable beams or posts 14, which are secured at their top and bottom in any suitable manner. For instance, the bottom may be secured to the floor of the mine and the top of the roof or side wall of the mine adit. Mounted transversely of the tracks 10, and mounted on the top of the beams 14, are the T beams 15, which are held in place by suitable bolts or the like, which are fastened to the upper end of the post 14. Secured beneath one of the cross T beams 15 is a yoke 17 which is held in place by means of the bolts 18. A plate 17' is connected to the yoke 17 by means of bolts 16'. On the under side of the plate 17, there is provided a lever 19 which is pivoted intermediate its ends to the plate by means of a bolt 20, as is clearly illustrated in the drawing. On the under side of the plate 17', is also provided an arcuate sliding bar 21 with one end portion of the lever being held between this bar and the plate. On this bar 21 is slidably mounted one end of a spring 22, the other end of which is connected to the lever at a point close to the opposite end of said lever as indicated at 23. At each end of the lever is connected a flexible traction member 24. The plate 17' has certain portions cut out and turned down as at 25 to form stops to limit the movement of said lever.

A bracket member 26 is carried by the outer member 15 and is held in place by means of bolts 18, and on this plate is pivoted the angular portion of a bell crank 27, and to one arm of this bell crank is connected the tubular link 28 which extends toward the lever 19. To the lever 19 is connected a link 29 which telescopes in the tubular link 28 and is held in an adjusted position by means of a pin 30 passing through one of a series of openings 31 formed in the link 28. Thus, the shoe portions 28 and 29 constitute an adjustable plate member.

A second bracket member 32 is mounted on one of the posts 14, and a vertical link 33 is pivotally mounted thereon by means of a bolt or the like 34. The upper end of the vertical link 33 is pivotally connected to the longitudinal link 35, by means of a bolt or the like 36, the opposite end of the longitudinal link 35 being connected to the other arm

of the bell crank 27. The lower end of the vertical link 33, is pivotally connected to the bar 37, which in turn carries the tie rod 13. It will be observed from the drawing this 60
5 operating mechanism is at proper height above the rails to be manipulated by a person on a mine car approaching a switch and it will be noticed that, for the sake of convenience the switch points have been shown 65
10 as closely adjacent to the position of the operating mechanism, but may be at any position from the switch desired. Thus the operating can be located as far from or close to the switch point as found desirable under 70
15 the conditions prevailing at the point at which this apparatus is to be installed.

In operation, a person on a train approaching the switch point can by grasping one of the cords 24 impart movement to the link 19, 75
20 which in turn will rock the telescopic sections 28 and 29 which will rock the bell crank 27, which will move the vertical link 33, thereby causing the rod 37 to move the switch point. It will be seen, that the pivoted lever 19 will be absolutely prevented 80
25 from accidentally becoming misplaced until one of the operating cords 24 has been manipulated, due to the fact that the spring 22 slides from one end of the arcuate member 30
21 to the other. As the spring 22 is connected near one end of the pivoted lever 19 and has sliding engagement with the arcuate member 21 the spring 22 which is under tension at all times will slide along the arcuate member whenever the lever 19 is moved. 85
35

It is to be understood that the form of my invention herewith shown and described is to be taken as a preferred embodiment of the same, and that various changes in shape, 90
40 size and arrangement of parts may be resorted to, without departing from the spirit of my invention or the scope of the subjoined claims.

Having thus described the invention what 45
45 is claimed as new is:

1. In a device of the kind described, a plate, means for securing said plate in an elevated position above a railroad rail, an arcuate sliding bar having its ends secured 50
50 to the under side of said plate and its body traversing the plate transversely and in spaced relation thereto, a lever pivoted intermediate its ends to the under side of said plate one end of said lever extending between the bar and the plate, a spring having one 55
55 end connected to the lever adjacent its remaining end and the other end slidably mounted on said bar, means for connecting

said lever to a switch, and means for moving the lever. 60

2. In a device of the kind described, a plate, means for mounting said plate in an elevated position above a railroad rail, an arcuate sliding bar having its ends secured to the under side of said plate and its body traversing the plate transversely and in spaced relation thereto, a lever pivoted intermediate its ends to the under side of said plate, one end of said lever extending between the bar and the plate, a spring having one end connected to the lever adjacent its remaining end and the other end slidably mounted on said bar, means connecting said lever to a switch, a bracket mounted above said railroad track, a bell crank pivoted at its angle to said bracket, an adjustable link connecting one arm of the lever with one arm of the bell crank, a post extending vertically adjacent the bell crank, a lever pivoted mounted on said post, a link connecting the remaining arm of the bell crank and the upper end of said pivoted lever, a link extending from the lower edge of said pivoted lever, and means to operate said device. 70
75

3. In a device of the kind described, an elevated plate positioned above a railroad rail, an arcuate bar mounted on the lower side of said plate, a lever pivoted to said plate on the under side thereof, a spring having one end connected to one end of the lever, the other end thereof being slidably mounted on said bar, means for connecting said lever to a switch and means for moving the lever. 80
85

4. In a device of the kind described, a plate, means for securing said plate in an elevated position above a railroad rail, an arcuate sliding bar having its ends secured to the under side of said plate and its body traversing the plate transversely and in spaced relation thereto, a lever pivoted intermediate its ends to the under side of said plate, one end of said lever extending between the bar and the plate, a spring having one end connected to the lever adjacent the remaining end and the other end slidably mounted on said bar, depending gears carried by said plate to restrict the movement of said lever, means for connecting said lever to a switch and means for moving the lever. 100
